(57) **CLAIM**

The ornamental design for a portable urinal, as shown and described.

DESCRIPTION

FIG. 1 is a perspective view of the portable urinal; FIG. 2 is a front elevational view of the portable urinal; FIG. 3 is a rear elevational view of the portable urinal; FIG. 4 is a left side elevational view of the portable urinal; FIG. 5 is a right side elevational view of the portable urinal; FIG. 6 is a top plan view of the portable urinal; and, FIG. 7 is a bottom plan view of the portable urinal.

The broken line showing in FIGS. 1 through 7 are for illustrative purposes only and forms no part of the claimed design.
